UNITED STATES PATENT OFFICE

WILLIS H. CARRIER, OF ESSEX FELLS, NEW JERSEY, ASSIGNOR TO CARRIER ENGINEERING CORPORATION, OF NEWARK, NEW JERSEY

REFRIGERATION

Application filed October 15, 1926. Serial No. 141,857.

This invention relates to refrigeration and has for an object to provide an improved method of refrigeration, which will have a definite and uniform and dependable performance; according to which the apparatus required may be reduced to a minimum; and which will be relatively simple, compact, efficient, and economical in operation, and inexpensive.

Various other objects and advantages will be apparent from the following description of an embodiment of the invention and the novel features will be particularly pointed out hereinafter in connection with the appended claims.

The accompanying drawing illustrates diagrammatically a simple system constructed in accordance with this invention.

In the illustrated diagrammatic embodiment of the invention, an evaporator 1, condenser 2 and compressor 3 are connected in series with one another by pipes 4, 5 and 6, so as to form a closed circuit through which a refrigerant may be circulated. Pipes 7 and 8 leading to the condenser provide a cooling medium for cooling and condensing the compressed vapor drawn from the evaporator by the compressor 3.

The liquid refrigerant delivered to the evaporator 1 from the condenser may be given a local circulation through the evaporator when the evaporator is of the unsubmerged type, as shown. In the unsubmerged type, the evaporator may contain a plurality of pipes through which the liquid to be cooled is circulated, and a suitable device 10 supplies the liquid refrigerant continually to the pipes to flow in a thin film thereover. The supply device 10 may be supplied with the liquid refrigerant through a pipe 11 leading from the circulating pump 12, which is in turn connected by pipe 13 to the lower part of the evaporator. The lower part of the evaporator may serve as a reservoir for the excess refrigerant, so that the spray de-

vice and circulating pump will be continuously supplied under all operation conditions, and the quantity of refrigerant circulated locally in the evaporator is always considerably in excess of the amount being evaporated.

The vapors from the evaporator are drawn off by the pipe 4, compressed in the compressor 3, and continued through pipe 5 to the condenser where they are cooled and liquefied.

The refrigerant used is methylene chloride, having the formula CH_2Cl_2 . The commercial methylene chloride, in addition to pure methylene chloride, contains higher and lower chlorinated products of this series of compounds which affect the temperatures between which it boils. For example, some samples of the commercial product at atmospheric pressure begin boiling at 105° F. and finish at about 150° F., the constituents having the lower boiling points evaporating first, leaving behind those with higher boiling points. The more readily vaporized portions would be evaporated first to a greater extent than the others, and their vapors would in use be reduced in proportion to the others, by leakage and by loss with purged air. Consequently, the minimum boiling point of the refrigerant would gradually increase during use, diminishing the relative refrigerating capacity of the compressor, unless the losses were replaced as soon as they occur. With the refined product, from which the higher and lower chlorinated products have largely been removed, the range of boiling points is small, and hence this capacity diminution is so slight as practically to be negligible. These other higher and lower chlorinated products are preferably first removed from the commercial product, preferably by distillation, so as to obtain a refined, fairly pure product which is very uniform in quality and possesses a very definite and practically invariable boiling point. This refined product will boil between ap-

condensing and returning to the circulation, the evaporated methylene chloride vapors.

6. The process of refrigeration which comprises passing methylene chloride as a film over unsubmerged evaporating surfaces, causing evaporation of such film, compressing by centrifugal action the evaporated vapors, condensing the compressed vapor and returning the condensed vapor as a film to said surfaces.

10 7. A process of refrigeration which comprises evaporating, compressing by centrifugal action, and condensing methylene chloride under pressures not materially exceeding approximately atmospheric pressure.
